INVENTOR
Percy H. Thomas
BY
Samuel G. Marshall
ATTORNEY

UNITED STATES PATENT OFFICE.

PERCY H. THOMAS, OF UPPER MONTCLAIR, NEW JERSEY, ASSIGNOR TO WESTINGHOUSE ELECTRIC & MANUFACTURING COMPANY, A CORPORATION OF PENNSYLVANIA.

ELECTRIC INSULATOR.

Original application filed August 29, 1913, Serial No. 787,243. Divided and this application filed February 8, 1918. Serial No. 215,972.

To all whom it may concern:

Be it known that I, PERCY H. THOMAS,
a citizen of the United States of America,
and a resident of Upper Montclair, county
of Essex, State of New Jersey, have invented
certain new and useful Improvements
in Electric Insulators, of which the following
is a specification.

My invention relates to electric insulators of the class particularly adapted for high tension electric lines although it may be used as well in connection with other electrical uses than with high tension. It is desired, among other objects, to provide an insulator of the suspension type which is adapted for extra-high tension service. Other objects, advantages and purposes of this type of insulator are set forth at greater length in the specification of my Patent No. 1,273,015, issued July 16, 1918, to which reference is hereby expressly made.

In the following I have described, in connection with the accompanying drawings, different forms of devices illustrating the application of the principles of my invention.

In the drawings Fig. 1 is a vertical sectional view of an insulator showing one way of practicing my invention; Fig. 2 is a top plan view of the device shown in Fig. 1 on a larger scale with the rain guard removed; Fig. 3 is a sectional view, partly broken away, of the parts shown in Fig. 2 along the line G—H; and Fig. 4 is a vertical sectional view of a modification of the type of insulator shown in Fig. 1.

Similar numerals of reference indicate similar parts throughout the several views.

40 In constructing the main body of my insulator I prefer to use a material having a high dielectric quality and one capable of being obtained of high quality and of great uniformity. Porcelain or glass are suitable materials for the purpose. In cementing certain of the parts together any suitable cement may be used and either Portland cement or cement made of litharge and glycerine will give good satisfaction. The metal parts of the insulator may be of any suitable metal giving the desired mechanical strength and malleable cast iron or steel forgings are suitable for the purpose. The rain guards which are adapted

to improve the electrical efficiency of insulator and to control the distribution of the electrical field may be of any suitable material such as galvanized iron.

Figs. 1, 2 and 3 show an insulator comprising a cylinder 83 of dielectric material provided with circular flanges 84—84 and a bridge 85 separating the two ends of the cylinder from each other. Each end of the cylinder is provided with recesses 86 arranged circumferentially (Fig. 2) of the respective ends of the cylinder. The cylinder at each side of recesses 86 is flared outwardly to form a strengthened wall for the recesses 86. 87 are metal cap pieces carrying pins 88 adapted to be cemented in recesses 86. Rain guards 89 are preferably integral with caps 87. The periphery of each rain guard 89 is provided with a rounded edge as shown. Rings 90 are carried by the cap pieces 87. This form provides a large number of small points of application of strain to the insulating material, which relieve the latter mechanically and at the same time is simple and economical to construct.

Fig. 4 shows an insulator comprising a plurality of cylinders of dielectric material, cylinders 91—91 being similar to each other and each closed at one end by a bridge 92 of dielectric material. The connection between the cap pieces 87 and the cylinders 91 is somewhat similar to that described in connection with the insulator shown in Fig. 1. Cylinders 91 and the intermediate cylinder 93 are joined together by pins cemented in recesses at the adjacent ends of said cylinders. Opposite the recesses formed to receive the connecting pins the respective cylinders are flared outwardly as shown at 94 and also provided with ribs 95. The purpose of the flared out portions and of the ribs 95 is to strengthen the dielectric material opposite said recesses. The caps 87 are connected to the respective ends of the cylinders 91 by means of pins 96 the lower ends of which are cemented in the recesses 86 in the ends of the cylinders while the upper ends are provided with heads 97 resting on washers 98 of any suitable material such as asbestos, leather, lead, etc. the shanks of the pins having a slight play in perforations 99 through the

cap pieces 87, the cap pieces being provided with suitable recesses or shoulders 100 to receive the heads 97 of pins 96. This construction is especially effective in relieving the insulating material from all stresses due to the expansion, contraction or deformation of the cap pieces 87. Ribs 101 are also shown as being disposed adjacent the flared outside portions of cylinders 91 opposite the recesses to provide additional strengthening means for the dielectric material.

It is obvious that I do not restrict myself to any particular type of construction, the forms shown being simply illustrative of various ways of carrying out the principles of my broad idea.

I claim:

1. An insulator comprising a body member of dielectric material having a plurality of laterally spaced symmetrically disposed longitudinal recesses at one end, said body member being of greater transverse area adjacent to said recesses than at an intermediate portion of the body member to compensate for the dielectric material removed from the recesses, and a longitudinal tension member secured in position in each of said recesses.

2. An insulator comprising a body member of vitreous material having a plurality of laterally spaced symmetrically disposed longitudinal recesses at one end, said body member being flared outwardly adjacent to said recesses to increase the transverse area thereof and to thereby compensate for the loss of the dielectric and mechanical strength of the material removed from the recesses, and longitudinal tension members secured in position in said recesses.

3. An insulator, comprising a plurality of units of dielectric material arranged end to end and each having a plurality of spaced circumferentially disposed recesses at each end, metallic tension members secured in position in said recesses for rigidly connecting said units to form a compound unit, a cap piece arranged at each end of said compound unit, and a plurality of metallic members secured in the outer end recesses of the end units for securing said cap pieces in place, the dielectric material, being thicker adjacent to the points of attachment of the metallic members to compensate for loss of

dielectric and mechanical strength in the material removed from said recesses.

4. An insulator, comprising a body portion of dielectric material, cap pieces at the respective ends, a plurality of metallic tension members at each end of the insulator secured in recesses in said body portion and serving to secure the cap pieces in place, and a rib on the dielectric material adjacent to each of said recesses.

5. In a tension insulator, a body portion of brittle material having end recesses, a cap piece at each end of the body portion, a plurality of metallic members at each end secured in the recesses in the body portion and engaging the cap pieces, and means in the cap pieces for loosely taking the load of said metallic members on said cap pieces, whereby freedom for expansion and deformation is secured.

6. In a line insulator in which a tension load is transmitted by means of vitreous insulating material, means for dividing the load on said insulator between a plurality of attachment points, said means including metallic parts provided with a physical clearance whereby opportunity is provided for free expansion and deformation of the several members of the insulator.

7. An insulator comprising a tubular body portion, said body portion being thicker between its inner and outer longitudinal surfaces adjacent to one end than at an intermediate portion thereof and having a plurality of equally circumferentially spaced longitudinal recesses between said surfaces and a plurality of longitudinal tension members secured in position in said recesses.

8. An insulator comprising a body portion of dielectric material, cap pieces at the respective ends thereof and a plurality of metallic members at each end of the body portion secured in recesses in said body portion and serving to secure the cap pieces in place, the dielectric material being shaped adjacent to said recesses to compensate for loss of dielectric and mechanical strength in the material removed from said recesses.

In testimony whereof I have signed this specification.

PERCY H. THOMAS.

Witness:

GEORGE F. WILSON.
